DOOR SILL

Wallace W. Miller, 205 N. 3rd, El Cajon, Calif.

Filed July 12, 1960, Ser. No. 61,316

Term of patent 14 years

(Cl. D13—6)

FIGURE 1 is a perspective view of a door sill, showing my new design;

FIGURE 2 is a bottom plan view thereof;

FIGURE 3 is a side elevational view, as taken from the left side of FIGURE 4; and

FIGURE 4 is an end elevational view thereof.

The door sill is broken away in the center thereof in FIGURES 1, 2 and 3 to indicate indeterminate length.

I claim:

The ornamental design for a door sill, as shown and described.
